UNITED STATES PATENT OFFICE.

CHARLES HOWARD SMITH, OF SHORT HILLS, NEW JERSEY, ASSIGNOR TO INTERNATIONAL COAL PRODUCTS CORPORATION, OF RICHMOND, VIRGINIA, A CORPORATION OF VIRGINIA.

FURNACE-RETORT.

1,413,801.

Specification of Letters Patent. Patented Apr. 25, 1922.

Application filed April 24, 1919. Serial No. 292,400.

To all whom it may concern:

Be it known that I, CHARLES H. SMITH, a citizen of the United States, and a resident of Short Hills, county of Essex, and State of New Jersey, have invented certain new and useful Improvements in Furnace-Retorts, of which the following is a specification.

The present invention has as its basis a furnace-retort which in some respects may be considered a modification of or an improvement upon the furnace-retort that is the basis of my copending application Serial No. 217,764, filed February 18, 1918, entitled Furnace-retorts.

In the furnace-retort shown in the drawings of said application the retort is defined in a main wall construction which includes what is described as (a) an inner wall portion—frequently referred to as a horizontally extending tubular inner wall construction or retort shell—within the wall of which or about which walls are combustion flues that extend along the inner wall portion of the retort; (b) a relatively heavy construction of fire-brick that provides an intermediate wall or strengthening masonry wall construction about the inner wall portion and which intermediate or strengthening wall also performs the function of storing heat transmitted to it from the flues constituting the combustion chamber of the furnace; and (c) an outer masonry construction of brick commercially known as Sigur brick that serves as a layer of heat insulating material about the intermediate wall. It will here be remarked that Sigur brick is a trade name for a brick comprising largely, if not wholly, diatomaceous earth. This material is sometimes sold under the trade name "Silocel." Such brick can be made by grinding said material, by pressing, and by baking, or the desired heat insulating brick may be obtained in some localities by cutting the brick from solid rock—sometimes as mined.

The furnace-retort shown in the drawings of said application is also provided with a mixing and conveying means having a pair of parallel cooperating shafts with paddles thereupon arranged so that the paddles on one shaft overlap the paddles on the other shaft. This mixing and conveying means, as the name implies, is relied upon to mix or agitate the material within the retort and also to convey the material from what is

known as the charging end of the retort to 55 what is known as the discharging end.

The furnace-retort which is the basis of the present application is shown as having the same general features of construction.

In the construction shown in said application the combustion flues extend the full length of the retort shell; or, in other words, the fuel for supporting combustion is shown as entering the combustion flues at the charging end of the retort, and the products of combustion as leaving the flues at the discharging end of the retort.

In the furnace-retort which is the basis of the present invention the combustion flues are constructed so that each flue extends only 70 about half the length of the furnace, and the flues are arranged in sets, one set at and along the charging end portion or charging end half of the inner wall of the furnace-retort and the other set at and along the discharging end portion or discharging end half.

Fuel is supplied to the flues which are at or along the charging end of the retort, preferably at the outermost end of each flue, to wit, the flue end at the charging end of the furnace, and fuel is supplied to the flues which are at or along the discharging end of the retort, preferably at the outermost end of each flue, to wit, the flue end at the discharging end of the furnace. The products of combustion pass from the innermost end of each flue, to wit, the end at or adjacent to the transversely extending central portion which is about the inner wall construction 90 and pass into a common flue or flues leading from said central portion. Each individual combustion flue is preferably provided with a damper for controlling the flow of products of combustion therefrom to the main or common flue or flues. By this arrangement and control of the combustion flues a finer degree of regulation of the heat conditions within the furnace-retort is attainable than is the case where the combustion flues extend the 100 full length of the inner wall of the retort.

The invention relates to the novel features of construction referred to as well as to others hereinafter clearly set forth.

As illustrating a specific embodiment of 105 the invention reference is made to the accompanying drawings forming a part of this specification and in which drawings,

Figure 1 is a vertical, longitudinal view, in section, of the furnace-retort. This is a view taken as on the planes indicated by the broken lines 1—1 of Figure 2 looking 5 in the direction of the arrows.

Figure 2 is a vertical transverse sectional view of the furnace-retort. This is a view taken as on the planes indicated by the broken line 2—2 of Figure 1 looking in 10 the direction of the arrows.

Figure 3 is a horizontal longitudinal sectional view of the furnace-retort and is a view taken as on the planes indicated by the broken line 3—3 of Figure 2 looking in 15 the direction of the arrows. In Figure 2 the furnace-retort is shown as resting upon a suitable foundation and from Figures 1, 2 and 3 it will be seen that the furnace-retort has a longitudinally extending tubular inner wall construction or retort shell surrounded by intermediate or strengthening masonry wall construction. It will 20 also be seen these walls are constructed so as to provide two sets of combustion flues, one at the charging end portion or half of the retort and the other at the discharging end portion or half, which combustion flues constitute the combustion chamber of the furnace of the furnace-retort, and that these 25 two sets of combustion flues deliver their products of combustion into transversely extending waste gas or waste heat flues located about the central portion of the furnace-retort and from which the waste gases are 30 conducted to any desired place, as, for example, to recuperators, to regenerators, or to a stack.

Figure 4 is a vertical transverse sectional view of the furnace-retort and is a view 40 taken as on the plane indicated by the line 4—4 of Figure 1 looking in the direction of the arrows. This view has been included to illustrate the arrangement of the longitudinally extending combustion flues and 45 burner openings therefor at the charging end of the furnace.

Figure 5 is a vertical transverse sectional view of the furnace-retort taken as on the plane indicated by the line 5—5 of Figure 50 1 looking in the direction of the arrows. This view has been included to show the dampers which control the flow of the products of combustion from the flues of one set of combustion flues into the waste heat 55 flue corresponding thereto.

Figure 6 is a vertical sectional view of the furnace-retort taken as on the plane indicated by the line 6—6 of Figure 1 looking in the direction of the arrows. This view 60 shows the arrangement of the burner openings at the discharging end of the furnace. From Figures 4, 5 and 6 the mixing and conveying means has been eliminated, this feature being sufficiently shown in other figures of the drawings.

Figure 7 is a partial sectional view taken as on the planes indicated by the broken lines 7—7 of Figure 2 looking in the direction of the arrows. In this view the construction of the dampers for the upper half 70 of the furnace between the combustion flues on the one hand and the waste heat flues is clearly illustrated.

Figure 8 is a view illustrating the structure that provides the several combustion flues about the retort. This is a view of the structure as it would appear if unrolled and placed upon a flat surface and it may be considered as a view showing the development and arrangement of the sets of 80 flues relative to each other. The upper half of this view clearly illustrates the flue arrangement and may be looked at as an interior view of the tubular inner wall construction or retort shell when unrolled, 85 while the lower half may be considered as an interior view from which the retort shell providing the tubular inner wall construction has been removed, showing the intermediate or strengthening wall which 90 is behind it.

Referring now to the drawings in detail 1 designates the furnace-retort, 2 the retort proper and 3 the furnace proper thereof. The furnace-retort is supported upon suitable foundation, as 4. The retort 2 has an inner wall construction 5, frequently referred to as a longitudinally extending tubular inner wall construction and sometimes as the retort shell. This longitudinally extending tubular inner wall construction or retort shell 5 is surrounded by a masonry wall 6, frequently referred to as the intermediate wall construction and sometimes as the strengthening masonry 100 wall.

It will here be pointed out that this masonry wall construction 6 serves the function of means for storing the heat imparted to it as a result of the combustion which takes place in longitudinally extending combustion flues 7 that are in or defined by the tubular inner wall construction or retort shell 5 on the one hand and the strengthening masonry wall construction 6 on the other.

In the construction of furnace as shown there appears a layer of heat insulating brick 8—such bricks as are known in the trade as Sigur brick or Silocel and this masonry construction is shown as enveloped in a metallic shell 9, the lower half of which is composed of members 10 bolted together and the upper half of which is composed of wrought metal plates 11 bolted to each other and also to the members constituting the lower half. In order to permit expansion of the masonry structure within the shell each of the bolts connecting the sections may be provided with wood washers, as a, which 120 125 130

will yield enough to permit the desired expansion without detrimental effect on the parts united by them. The tubular inner wall construction or retort shell may be 5 considered to be composed of a number of hollow tile members, as 12, 13 and 14, each of which has longitudinally extending rib portions, as 15. These rib portions 15 co-operate with other longitudinally extending 10 rib portions 16 that are on or built-in the masonry strengthening wall construction 6 and from an inspection of the drawings, particularly Figures 4 and 5, it will be observed that the longitudinally extending 15 combustion flues 7 are provided in or defined by the tubular inner wall construction or retort shell 5 on the one hand and the strengthening masonry wall construction 6 on the other, and particularly by such portions, as 17, of the tubular inner wall construction—portions at the exterior of the tubular inner wall construction and between the longitudinally extending rib portions 15—longitudinally extending rib portions 15, 20 longitudinally extending rib portions 16 of the strengthening wall construction 6 and the interior portions 18—portions on the interior of the masonry strengthening wall construction between the longitudinally extending rib portions 16. A centrally located 25 transversely extending rib portion or partition 19, which includes the transversely extending rib portion 20 on the tubular inner wall construction or retort shell and transversely extending rib portion 21 on the masonry strengthening wall construction, is located at or near to the central portion of the furnace; in other words, in a transverse belt which is at, about or near the central 30 portion of the furnace. This rib portion or partition 19 may be considered to encircle or extend about the tubular inner wall construction so as to divide the combustion space of the furnace into two parts, one part 35 located at the charging end or charging half of the furnace and the other part located at the discharging end or discharging half of the furnace.

An inspection of the drawings will also 40 make it clear that there are located at each side of the centrally located transversely extending rib portion or partition 19 two transversely extending waste gas or waste heat flues 22, 23, one located at the charging 45 face of the rib portion or partition 19 and the other located at the discharging face of the rib portion or partition, but both located about the central portion of the furnace.

From Figures 1, 7 and 8, it will be observed that the combustion flues 7 at the charging end or half of the furnace deliver the products of combustion into the waste heat flue 22 but that the flow of gases from 55 these combustion flues into the waste gas or

waste heat flue 22 is controlled by dampers 24 and 25. The combustion flues 7 for the discharging end or half of the furnace deliver their products of combustion into the waste heat flue 23 past another set of like 70 dampers 24 and 25.

Referring now to the damper construction, it will be observed that each damper 24 is a solid block of material slidably mounted in a flue and has a lip 26 that may be moved 75 toward or from a rib 27 of the tubular inner wall construction or retort shell by a rod, as 28, sliding the damper 24 whereby the opening between the lip 26 on the one hand and the rib 27 on the other is readily 80 controlled as to its area. The dampers 24 are used to control the flow from the combustion flues in the lower half of the furnace. The dampers for the upper half of the furnace have been designated as 25 and 85 90 are in effect a modification of the dampers 24. The dampers 25, however, each has a main body member 29 supported on spaced longitudinally extending legs 30 and the body member 29 carries a transversely extending lip 31 which is movable toward and from the transversely extending rib portion 27, and the area of the passage between the lip 31 on the one hand and the rib portion 27 on the other is controlled by a movement 95 of this damper 25 in a manner similar to that in which the damper 24 controls the passageway leading from its corresponding flues to the waste heat flue. A damper, as 100 24 or 25, is provided for each combustion flue and it will therefore be seen that the flow of the products of combustion from each combustion flue to the waste heat flue is under the control of the operator.

The waste heat flues 22 and 23 pass 105 through the side walls of the furnace-retort, as this portion of the retort wall may be referred to, as is clear from Figures 2 and 3, and the flow from each of the waste heat flues is subject to the control of dampers 110 115 32 prior to the products of combustion being conducted from the furnace-retort, as to the main flue leading to the stack 33.

A gas burner is provided to supply fuel and to permit the entrance of air to the interior of the outer end portion of each combustion flue; in other words, burners are provided at the charging end of the furnace for supplying gas to and permitting air to enter the charging end portion of the flues 120 at the charging portion or half of the furnace and burners are provided at the discharging end of the furnace for supplying gas to and permitting air to enter the discharging end portion of the flues at the discharging portion or half of the furnace. These burners are designated, as by 34 and 35, and each comprises a tube for supplying heating gas to the interior of the combustion flue supplied thereby and a damper 34^a 130

for regulating the flow of air, that supports combustion, into the flue.

In furnaces of this type it has been found important to be able to control the heat conditions about each portion of the shell. For example, it may be desired, as the furnace is operating, to impart a greater heat to the lower side portions of the charging end and a lesser heat to certain portions of the dis-
10 charging end. It may even be desired to cut off the heat along the entire upper half of the shell or only along one end of the upper half of the shell. With the burners, the flue arrangements and dampers herein de-
15 scribed the desired condition can be readily reached.

The gases and vapors driven off during the carbonizing operation are withdrawn through piping 36. In the drawings in this
20 application only one set of piping has been indicated but a plurality of piping might be employed, if desired, such as shown in my co-pending application Serial No. 217,764.

The upper half of the tubular retort shell
25 is in the form of an arch, being formed as such by the hollow tiles or blocks as 13 having the ribs as 15. It has been heretofore pointed out that the ribs 15 which extend outwardly co-operate with the rib portions
30 16 which extend inwardly that are on or built in the masonry strengthening wall construction, to wit; the masonry immediately surrounding the inner wall construction. On the drawings, there are indicated in several places expansion spaces as 37 which as the name implies have been provided to allow for the circumferential expansion of the inner wall construction or retort shell, and it will here be remarked that where the inner
35 construction is formed of a carborundum tile—or in fact of other material—and the immediately surrounding wall is of masonry such as fire brick that it has been found advisable to have the expansion spaces placed
40 as indicated.
45

In the construction as shown the lower half of the tubular inner wall construction or retort shell supports the upper half, to wit, the arch portion and consequently the
50 members of the lower half rest directly upon the surrounding masonry construction which is below it.

In order to provide for circumferential expansion in the lower half an expansion
55 space is provided as at 38, that is between the two rows of blocks along the lower longitudinal central portion. In the building of the furnace this space 38 may be filled with material such as sheets of cardboard which
60 can gradually carbonize and allow for the desired expansion. This cardboard can be relied upon to hold or maintain the adjacent blocks in the proper spaced relationship during the constructing of the furnace.

65 No attempt is herein made to describe in

detail the operation of the furnace or the detailed construction of the mixing and conveying means, or other details in the furnace, all such details being clear from the accompanying drawings and from an understanding of the structure shown and described in the aforesaid co-pending application.

What is claimed is:—

1. A furnace-retort having a longitudinally extending retort shell within which a carbonizing or coal distilling operation is performed, said furnace-retort also having means for mixing the charge within the retort shell and for conveying the charge longitudinally along the interior of the retort shell, the furnace-retort construction being such that there are two sets of longitudinally extending combustion flues arranged about the retort shell, one set for each half of the retort shell, the flues in each set extending along the retort shell, terminating about midway its length and opening into a waste heat flue arranged to receive the products of combustion delivered to it from the flue in the set in which the combustion flue is included.

2. A furnace-retort having a longitudinally extending retort shell within which a carbonizing or coal distilling operation is performed, said furnace-retort also having means for mixing the charge within the retort shell and for conveying the charge longitudinally from the charging end of the retort shell to the discharging end thereof, the furnace-retort being characterized by two sets of combustion flues arranged about the lower portion of the retort shell and delivering products of combustion into a centrally arranged waste heat flue construction, each flue in each set extending longitudinally from an end portion of the retort shell toward the centrally arranged waste heat flue, each flue in the other set extending along the discharging end of the retort shell and terminating about midway the length of the retort shell.

3. A furnace-retort having a longitudinally extending retort shell portion, in which retort there is means for agitating or mixing the charge and for conveying the charge along the interior from the charging end to the discharging end thereof, the combustion chamber of the furnace of the furnace-retort comprising longitudinally extending combustion flues about the shell portion, which combustion flues are arranged in sets one set at the charging end of the retort and the other set at the discharging end, means at the charging end of the furnace-retort for controlling the supply of fuel and flow of air to the interior of the outer end portions of the combustion flues in one set, means at the discharging end of the furnace-retort for controlling the

supply of fuel and the flow of air to the interior of the outer end portions of the combustion flues in the other set, two transversely extending waste heat flues located about the central portion of the furnace, there being a waste heat flue for each set of combustion flues, a damper controlled opening between each combustion flue of the set at the charging end of the furnace through which products of combustion pass into one of said waste heat flues, and a damper controlled opening between each combustion flue of the set at the discharging end of the furnace through which the products of combustion pass to the other waste heat flue.

4. A furnace-retort having a longitudinally extending retort shell in which there is means for agitating or mixing the charge and for conveying the charge longitudinally along the interior of the retort from the charging end to the discharging end thereof, the furnace of the furnace-retort having a combustion chamber which is provided by longitudinally extending combustion flues arranged about the retort shell, the flues being arranged in sets, the combustion flues in one set each extending along the charging end half of the retort and the combustion flues in the other set each extending along the discharging end half of the retort, said combustion flues terminating at or adjacent to the central transversely extending portion of the shell, means for supplying fuel and for permitting air to enter said combustion flues, the furnace having transversely extending waste heat flues arranged so as to receive the products of combustion from said combustion flues, and dampers regulating the openings or passageways leading from the combustion flues to the corresponding waste heat flues.

5. A furnace-retort having a longitudinally extending retort shell in which there is means for agitating or mixing the charge and for conveying the charge longitudinally along the interior of the retort from the charging end to the discharging end thereof, the furnace of the furnace-retort having a combustion chamber comprising longitudinally extending combustion flues arranged about the exterior of the retort shell, which flues are arranged in two sets, the combustion flues in one set each extending along the charging end portion of the retort and the combustion flues in the other set each extending along the discharging end portion of the retort, said combustion flues terminating at or adjacent to the transversely extending central portion of the shell, means for supplying fuel and for permitting a controlled amount of air to enter said combustion flues, the furnace-retort having two transversely extending waste heat flues located at or near said cen-

tral portion each arranged so as to receive the products of combustion from one of said sets of said combustion flues, each waste heat flue having a damper for controlling the opening or passageway leading therefrom, each combustion flue having a damper at the opening or passageway leading from the combustion flue to the corresponding waste heat flue.

6. A furnace-retort the retort of which is provided in a longitudinally extending retort shell into which coal is fed at one end and from which the coal residuum is discharged from the other end, the furnace construction being such that combustion flues are provided each of which extends longitudinally from the charging end of the shell toward the central portion of the shell and delivers products of combustion into a waste heat flue arranged at the central portion of the shell, each of said combustion flues having a damper for controlling the flow of products of combustion from the combustion flue into said waste heat flues, the furnace construction also being such that combustion flues are provided each of which extends longitudinally from the discharging end of the shell toward the central portion of the shell and delivers products of combustion into a waste heat flue arranged at the central portion of the shell, each of said last-mentioned combustion flues having a damper for controlling the flow of products of combustion from the combustion flue to the waste heat flue.

7. A furnace-retort the retort of which is provided in a longitudinally extending retort shell into which coal is fed at one end and from which the coal residuum is discharged from the other end, the furnace construction being such that combustion flues are provided some of which extend longitudinally from the charging end of the shell toward the central portion of the shell and deliver products of combustion into a waste heat flue arranged at the central portion of the shell and some of which extend longitudinally from the discharging end of the shell toward the central portion of the shell and deliver products of combustion into a waste heat flue arranged at the central portion of the shell, each of said combustion flues having a damper for controlling the flow of products of combustion from the combustion flue into its waste heat flue.

8. A furnace-retort having a longitudinally extending retort shell into one end of which material is charged that is to be carbonized and from the other end of which the residuum is discharged, means at the exterior of said shell for providing longitudinal combustion flues extending to the central transversely extending exterior portion of the shell and arranged in sets about the shell, there being a set of combustion

- 6 flues for the charging end portion of the shell and another set of combustion flues for the discharging end portion of the shell, the construction also being such that there is a 5 waste heat flue provided for and common to each set of combustion flues, there being dampers for controlling the flow of products of combustion from the combustion flues of each set into the common waste heat flue 10 corresponding to that set, the furnace having means for supplying fuel to the interior of the combustion flues and dampers for regulating the amount of air supplied to the interior of the combustion flues. 15 9. A furnace-retort having a longitudinally extending retort shell into one end of which material is charged that is to be carbonized and from the other end of which the residuum is discharged, means at the exterior of said retort shell for providing longitudinally extending combustion flues that reach the central portion of the exterior of the retort shell but which are arranged in sets about the retort shell in such 20 a manner that there are combustion flues for the charging end portion of the retort shell and combustion flues for the discharging end portion thereof, the construction also being such that a waste heat flue is 25 provided for and common to the combustion flues in each set, there being dampers for controlling the flow of products of combustion from the flues in each set. 30 10. A furnace-retort comprising in combination a longitudinally extending retort shell surrounded by a fire-brick or strengthening masonry wall construction and between which said retort shell and said wall construction there are left spaces providing 35 the combustion chamber of the furnace of the furnace retort, the combustion chamber being divided into two parts by a transversely extending rib portion surrounding the transversely extending central portion of the retort shell, spaced longitudinally extending rib portions, in each of said parts, arranged about the retort shell and extending from each end of the retort shell toward but not to the transversely extending rib portion whereby there is provided for each 40 longitudinal half of the retort shell a set of longitudinally extending combustion flues 45 50 that discharge their products of combustion into a waste heat flue that is between the transversely extending rib portion on the one hand and the ends of the spaced longitudinally extending rib portions on the other, and dampers for controlling the flow of products of combustion from the combustion flues into the waste heat flue corresponding thereto. 55 60 11. A furnace-retort comprising a longitudinally extending retort shell surrounded by a fire-brick wall construction, between which retort shell and wall construction there are spaces providing the combustion chamber of the furnace of the furnace-retort, the combustion chamber being divided into two parts, one part located at one end and the other part located at the other end of the furnace-retort, each part having spaced 65 rib portions arranged about the retort shell and extending longitudinally toward the transversely extending central portion of the furnace-retort whereby there is provided for each of said parts a set of longitudinally extending combustion flues, the furnace construction being such that said combustion flues discharge their products of combustion into waste heat flues located at the central portion of the furnace-retort, the furnace 70 having dampers for controlling the flow of products of combustion from the combustion flues into said waste heat flues. 75 12. A furnace-retort having a longitudinally extending tubular shell formed of 80 blocks or tiles arranged so that there is a longitudinal row of blocks along each side of the lower longitudinal central portions and positioned so that an expansion space is left between said rows which are adjacent 85 to each other. 90 13. A furnace-retort having a longitudinally extending tubular shell formed of carbide blocks or tiles arranged so that a row of blocks extends along each side of the lower longitudinal central portions and is positioned so that an expansion space is left between the blocks in said rows which rows are adjacent to each other, and material such as cardboard in said space. 95 100 This specification executed the 15 day of April 1919.

CHARLES HOWARD SMITH.
